UNITED STATES PATENT OFFICE

161,647

ELECTRIC RANGE

Carl Reynolds, Jr., Birmingham, Mich., assignor
to AVCO Manufacturing Corporation, Cincinnati,
Ohio, a corporation of Delaware

Application March 24, 1950, Serial No. 8,738

Term of patent 14 years

(Cl. D81—4)

To all whom it may concern:

Be it known that I, Carl Reynolds, Jr., a citizen of the United States, residing at Birmingham, Michigan, in the county of Oakland, have invented a new, original, and ornamental Design for an Electric Range, of which the following is a specification, reference being had to the accompanying drawings, forming a part thereof.

In the drawings:

Fig. 1 is a top plan view of an electric range embodying my new design;

Fig. 2 is a front elevational view thereof; and

Fig. 3 is an elevational view of the right end thereof.

The left end of the range has not been illustrated but is substantially the same as the right end shown in Fig. 3.

I claim:

The ornamental design for an electric range, as shown and described.

CARL REYNOLDS, JR.
